UNITED STATES PATENT OFFICE.

CLIFTON E. MOORE, OF CHICAGO, ILLINOIS, ASSIGNOR OF ONE-HALF TO W. H. DANGEL,
L. D. WOODRUFF, AND M. W. DANGEL, ALL OF CHICAGO, ILLINOIS.

FLYING MACHINE.

Application filed March 11, 1926. Serial No. 93,824.

The present invention has for its object to produce a simple and novel propeller and controlling means therefor, which will permit the propeller to exert a pulling force 5 along any radius of a large arc.

My improved propeller may be used either as the sole sustaining and propelling means for an aerial vehicle, or it may be employed to assist other means for raising or lowering 10 or moving a vehicle forwards or backwards.

A further object of the present invention is to produce a simple and novel propeller and controlling means therefor which will serve to lift an aerial vehicle, move it back- 15 ward and forward, and serve effectively to check the descent of the vehicle in the event of failure of power.

The various features of novelty whereby my invention is characterized will herein- 20 after be pointed out with particularity in the claim; but, for a full understanding of my invention and of its objects and advantages, reference may be had to the following detailed description taken in connection with 25 the accompanying drawings, wherein:

Figure 1 is a side elevation of a heavier than air vehicle, equipped with a lifting and propelling device arranged in accordance with my invention; Fig. 2 is a front elevation of the vehicle; and Fig. 3 is a section, on an enlarged scale, taken on line 3—3 of Fig. 2.

In the drawings I have illustrated my invention as applied to an aerial vehicle that 35 is heavier than air and, for the sake of brevity, I shall confine the detailed description to this particular embodiment, since the principles of operation applicable to other uses will be evident from an explanation of this 40 particular use.

Referring to the drawings, 1 represents a vehicle body or fuselage, underneath the front of which may be supporting wheels 2, while the rear end may be supported on a 45 trailing arm or stem 3. A frame 4 rigidly connected to the fuselage, rises therefrom. My improved propeller is mounted in the upper end of the frame. The upper portion of the frame comprises two separated side members 50 between the upper ends of which extends the propeller shaft 5. The propeller shaft is shown as having four radial arms or spokes 6 rigidly attached thereto near each end. Between the outer ends of each pair of 55 arms or spokes extends a rotatable shaft 7

that is parallel with the shaft 5. On each of the shafts 7 is fixed a vane, the four vanes being indicated at A, B, C and D. When the main shaft 5 revolves, the vanes rotate bodily about the long axis of this shaft and, in 60 order to cause the vanes to function as lifting and propelling devices, means must be provided to cause each to rotate about the long axis of its supporting shaft 7, as it revolves bodily about the shaft 5. In the arrangement shown, each of the shafts 7 has a sprocket wheel 8 secured thereto. An endless sprocket chain 9 passes around all of the sprocket wheels 8, so that when one of these shafts rotates about its axis, the remainder 65 are similarly rotated. Rotation of one of the shafts 7 about its axis may conveniently be effected by placing on the shaft 5 a sprocket wheel 10 that is loose on the shaft, so that it may be held stationary while the shaft rotates, and providing the shaft 7 with a sprocket wheel 11, around which and the sprocket wheel 10, a chain 12 passes. When the sprocket wheel 10 is held stationary, and the shaft 5 is rotated, the vanes will be 70 75 revolved bodily about the shaft 5 and will also revolve about their own axes of rotation. The vanes must not only revolve about their own axes, but each must rotate through an angle of only 180 degrees about its own axis 80 while it is traveling bodily through an angle of 360 degrees. To this end the sprocket wheel 11 is provided with twice as many teeth as the sprocket wheel 10, whereby the sprocket wheel 11 will make only half a revolution about its own axis while it is swinging 85 through an angle of 360 degrees about the main axis of the propeller.

In order to permit the vanes to be made light and at the same time to be rigid, each 90 may be provided with trusses 13, there being two of such trusses at each end, lying on opposite sides of the vane.

The propeller shaft may be driven in any suitable way as, for example, by a motor 14 arranged within the fuselage; the shaft 15 of the motor driving a countershaft through a sprocket chain drive 17, and the shafts 16 and 5 being connected by a sprocket chain drive 18.

When the propeller is rotated, its effect on the vehicle depends entirely upon the initial adjustment of the vanes. If this adjustment be such that the vanes occupy the position shown in Fig. 1, when one of the vanes is 110

at the top, the propeller rotating in a counterclockwise direction, the propeller will exert a lifting force that will raise the vehicle in a vertical direction. If the propeller be rotated in the opposite direction or, if the initial adjustment of the vanes be such that each is set at an angle of ninety degrees from the position shown in Fig. 1, the propeller will exert a downward pressure. If the vanes are initially adjusted so that each is turned somewhat in a clockwise direction from the position shown in Fig. 1, the propelling force will be divided between a vertical or lifting force and a horizontal force tending to move the vehicle toward the left. If the initial adjustment be in the counterclockwise direction, the propelling force will consist of a vertical component and a component tending to move the vehicle toward the right. The relative values of the vertical and horizontal components may be varied over a range that is practically infinite. It will thus be seen that if means are provided for varying the adjustment of the vanes at will, a vehicle may be lifted in substantially the vertical direction, be forced down vertically, or be lifted or lowered and at the same time moved backward or forward at any desired angle. In case the motor fails when the vehicle is in the air, the vanes will serve as planes that will permit the vehicle to glide to earth at a relatively low speed. This speed may be reduced to a minimum if the vanes are adjusted so that the upper one is horizontal, the lower one vertical, and the other two converging toward the top at an angle of 45 degrees.

In order to control the angular positions of the vanes with respect to the propeller as a whole, I have fixed to the sprocket wheel 10 another sprocket wheel 20. An endless sprocket chain 21 passes around the sprocket

wheel 20 and around a sprocket wheel 23 fixed to a shaft 22 rotatably supported in the lower portion of the frame and extending into the fuselage. On the end of the shaft 22, within the fuselage, is a hand wheel 24. By turning the hand wheel 24, the sprocket wheel 20, and therefore the sprocket wheel 10 may be shifted independently of any movement of the shaft 5, so as to vary what I have termed the initial adjustment of the vanes. In the arrangement shown, the sprocket wheel 20 may be turned through a complete revolution, thus permitting the vanes to be adjusted through an angle of 180 degrees.

The vehicle may be raised or lowered or be moved ahead or backward at any desired angle by rotating the propeller and adjusting the vanes. In order to steer the vehicle toward the right or left, additional means must be provided which, in the case of a simple machine such as illustrated, may consist of a vertical swinging tail 25 operated by cables or wires 26 extending forward to a controlling handle 27 arranged in the fuselage.

I claim:

In combination, an aerial vehicle, a single propeller above said vehicle comprising a frame rotatable about an axis transverse to the longitudinal axis of the vehicle and vanes directly supported on said frame for rotation about their central transverse axes lying parallel with the aforesaid axis, means for rotating said frame and simultaneously rotating each vane about its own axis at one-half the angular speed of the frame, and means operable from a point within the vehicle both with the frame rotating and when it is stationary to shift the vanes to vary their angle of contact.

In testimony whereof, I sign this specification.

CLIFTON E. MOORE.
